CLAIM

The ornamental design for a self-propelled and spin stabilized fempto satellite with a dual asymmetrical bifurcated dipole antennae kicker, as shown and described.

DESCRIPTION

FIG. 1 is an isometric view of the self-propelled and spin stabilized fempto satellite with a dual asymmetrical bifurcated dipole antennae kicker showing our new design;

FIG. 2 is a top view thereof;

FIG. 3 is a bottom view thereof;

FIG. 4 is a front view thereof; and,

FIG. 5 is a side view thereof.

The broken lines indicate the bounds of the claimed design and form no part of the claimed design.
